UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FEED MECHANISM.

1,313,148.

Specification of Letters Patent.

Patented Aug. 12, 1919.

Application filed March 19, 1917. Serial No. 155,903.

To all whom it may concern:

Be it known that I, ERASTUS E. WINKLEY, a citizen of the United States, residing at Lynn, in the county of Essex and State of Massachusetts, have invented certain new and useful Improvements in Feed Mechanism; and I do hereby declare the following to be a full, clear, and exact description of the invention, such as will enable others skilled in the art to which it appertains to make and use the same.

This invention relates to mechanism for feeding successive articles from a supply of such articles held or stored in stacked relation.

One object of the invention is to produce feed-mechanism of the kind in question, in which a considerable quantity of the articles to be fed may be stacked in a comparatively small space or compact form. To this end, it is proposed to employ, in place of the straight magazine or chute usually employed for holding stacked articles, a magazine which is curved so as to hold the articles in the form of a longitudinally curved stack. The curvature of the magazine may be of different characters, but in the most complete embodiment of the invention, it is proposed to employ a spiral or helical magazine, in which a considerable quantity of articles may be held in a space of comparatively small vertical extent.

Another feature of the invention resides in the employment of means, for advancing the articles in the stack, which are particularly adapted for use in connection with a curved stack. To this end the means in question are constructed and arranged to engage the surfaces of the stack at the outer and inner curves thereof, and are moved intermittently through suitably curved paths conforming, at least approximately, to the longitudinal curvature of the stack.

Another object of the invention is to provide especially for the feeding of articles which are wedge-shaped or tapering in one of their dimensions. In the manufacture of heels, it is common to employ wedge-lifts of leather, or other sheet material, and difficulty has been encountered heretofore in stacking and feeding such wedge-shaped lifts. In accordance with the present invention, the lifts, or other articles of tapering

form, are stacked in close contact, with their thicker and thinner extremities, respectively, together. This results in the formation of a longitudinally curved stack, such as the mechanism of the present invention is particularly adapted to hold and feed.

Another object of the invention is to produce feed-mechanism adapted particularly for feeding stacked articles of sheet-material, and in which articles may be readily and conveniently added to the stack whenever necessary. In previous mechanisms for the purpose, it has been common to employ followers of one form or another for pressing against the rearmost piece in the stack, to advance the stack through the magazine. When pieces are to be added to the stack in such an arrangement, it is usually necessary to remove or displace the follower temporarily, thereby interrupting the operation of the feed-mechanism. In accordance with the present invention, the use of such followers is eliminated, by the provision of means which act upon some or all of the articles in the stack by an edgewise clamping action, the articles being thereby gripped and advanced without the necessity of any engagement with their faces.

Other objects of the invention, and the features and construction and operation by which they are attained, will be set forth in connection with the following description of the illustrated embodiment of the invention.

In the accompanying drawings Figure 1 is a plan-view of a machine embodying the present invention; Fig. 2 is an elevation of the machine, looking upwardly in Fig. 1 and partly broken away to show the interior construction; and Fig. 3 is an elevation of the machine, looking from left to right in Fig. 1, and partly in section approximately on the line 3-3 in the latter figure.

The invention is illustrated as embodied in a machine particularly adapted for feeding wedge-shaped or tapering articles of sheet-material, such as wedge-shaped lifts for use in the manufacture of heels. The magazine comprises two angle-iron members 6 and 8 which are curved, in a helical form, about a cylindrical, central, vertical member 18. This member is coaxial with the helices formed by the members 6 and 8, so as to form a helical path of uniform

cross-sectional dimensions in which a helical stack of articles 16 may be supported and guided, these articles resting with their thinner edges against the member 18, while 5 their outer corners are engaged by the guide-members 6 and 8. The members 6 and 8 are supported by arms 10 projecting horizontally from uprights 12 which are fixed upon the stationary bed-plate 14 of the machine. 10 The central member 18, which is shown as tubular in form, is provided, at its lower end, with a depending cylindrical stud 20, which turns freely in a bearing-sleeve 22 on the base-plate 14 so that the member 18 is 15 free to rotate for a purpose which will be described.

The articles 16 are discharged successively from the lower end of the stack, and the lowermost article in the stack is pressed 20 against two vertical stop-arms 24 fixed upon the base-plate, as shown in Figs. 1 and 2. The articles are discharged by means of a feed-plate 26 which stands between the stop-arms and is provided, at its upper end, with 25 lugs 28 adapted to engage the upper edge of the lowermost article in the stack. The feed-plate moves vertically through an opening in the bed-plate 14, and it is actuated by connection with a feed-slide 30 which is 30 guided vertically in a slotted guideway 32 depending from the bed-plate.

The feed-slide is actuated by cam-mechanism, and for this purpose it is connected, by a short link 34, with one end, of a cam-lever 36, which is pivoted on a hanger 38 depending from the bed-plate. At its rear end the cam-lever carries a roller 40, which bears 40 against a cam 42 fixed upon a cam-shaft 44. This shaft turns in a hanger 46 depending from the bed-plate, and it is connected, by means of a sprocket-wheel and a chain 48, with any suitable source of power. A spring 49, attached to the cam-lever 36, maintains the roller in engagement with the cam, and 45 the cam is so shaped that at each rotation of the cam-shaft the feed-slide is once depressed and then raised again, thus drawing an article from the stack downwardly through the opening in the table.

50 The feed-mechanism may be employed in connection with any machine into which it is necessary to feed an article at regular intervals. A chute 50 is shown in the drawings as fixed to the base-plate, in position to receive the articles expelled by the feed-plate, and this chute may be arranged to conduct the articles to any required point of delivery.

Owing to the curvature and the slight in- 60 clination of the stack, the articles therein will not pass downwardly through the magazine under the effect of gravity alone, and means are therefore provided for advancing the stack in proportion as articles are dis- 65 charged from the lower end thereof. These

means comprise feed-clamps 52, in the form of arms which are fixed, in pairs, on four vertical shafts 54. The concaved inner surfaces of the arms may engage the outer or thicker edges of the articles 16 between the 70 members 6 and 8 of the magazine, as shown particularly in Fig. 3. By the use of four pairs of feed-clamps, each extending around approximately a quarter-turn of the rack, provision is made for operative engagement 75 with all of the articles from top to bottom of the illustrated magazine.

The shafts 54 are actuated both to throw the feed-clamps intermittently into and out of operative engagement with the articles, 80 and to move them, when in such engagement, in the direction of feed. To this end the shafts are carried by an annular member or feed-ring 56, which turns in horizontal bearings 58 and 60 formed in the bed-plate 14, as 85 shown particularly in Fig. 3. This ring is held to its bearings by two overhanging plates 61, which are fixed to the bed-plate and which engage raised bearing-surfaces 63 on the feed-ring. Each of the shafts 54 has 90 a bearing, at its lower end, in the feed-ring, while its upper end has a bearing in one of four uprights 62, rising integrally from the feed-ring. A collar 64, at the upper end of each shaft, supports the shaft by engagement with the upper end of the upright.

The operative surface of each clamp-member is curved to conform to the outer curved surface of the stack, and is provided with vertical teeth 66 to afford a secure hold upon 100 the articles 16. The shafts 54 are turned slightly to cause the teeth to engage the articles, and the feed-ring is then turned through a sufficient angle to advance the stack to the necessary extent. During this 105 movement, the feed-clamps press the articles radially inwardly, so that their inner edges are pressed firmly against the radial member 18, the articles being thus clamped by an edgewise pressure. When any substantial 110 number of articles is in the magazine, the frictional engagement of their inner edges with the member 18 causes the latter to be rotated. In this manner, the clamping engagement is properly maintained, even with 115 the uppermost articles in the stack, and these articles are properly advanced at both their outer and inner edges so as to maintain them in position in the stack. For this reason, articles may be introduced into the 120 stack at will during the times, in the operation of the machine, when the clamp-members 52 are swung out of engagement with the stack, and for the same reason the stack is properly advanced through the magazine 125 until nearly exhausted.

The movements, just described, of the shafts 54 and the feed-ring 56 are produced through the intermediation of a second annular member or actuating-ring 68, 130

which turns in a recess 70, in the bed-plate 14, just beneath the feed-ring 56. On the lower end of each shaft 54, a gear segment 72 is fixed, as shown particularly in section 5 at the left-hand portion of Fig. 1, and this segment engages teeth upon the actuating-ring 68. The outward swinging movement 10 of the clamp-member is limited by a stop-lug 74 projecting inwardly from the gear- 15 segment 72 and adapted to engage a stop-pin 76 depending from the feed-ring. The actuating-ring is also provided with gear-teeth which engage a gear-segment on one arm of a lever 78, which is pivoted on a 20 stud 80 depending from the bed-plate 14. The lever 78 is oscillated by cam-mechanism. For this purpose, it has an arm 82 which is pivoted to one end of a spring-housing 25 84. A rod 86 slides through the opposite end of the spring-housing and is provided with a head 88. A spring 90, coiled around the rod within the housing, acts against the head 88 and tends to slide the rod inwardly, this movement being limited, however, 30 by stop-nuts 92 threaded on the rod. The other end of the rod 86 is fixed in a yoke 94 pivoted to one arm of the bell-crank 96, and this lever is pivoted on a stud 98 depending from the bed-plate. The other arm 35 100 of the lever carries a roller 102 engaging a cam 104 on the cam-shaft 44. At each rotation of the cam-shaft, the cam-lever is operated to rock the lever 78 first in one direction and then in the opposite direction, thereby 40 producing an oscillation of the actuating-ring 68. This movement of the ring tends to oscillate the shafts 54, through the gear-segments 72, assuming that the feed-ring remains stationary. Movement of the feed-ring is 45 yielded resists by a spring-pressed friction-plug 106, which slides in a perforation in the bed-plate and presses against the periphery of the feed-ring. By means of the friction plug, movement of the feed-ring is resisted until the actuating ring 50 has moved far enough to cause the feed-clamps to be swung into engagement with and pressed against the articles 16. As soon as the swinging movement of the feed-clamps is thus arrested, the continued movement of the actuating-ring, since it can result in no further rotation of the shafts 54, causes a turning movement of the feed-ring, whereby the shafts are moved to cause the feed-clamps to advance the stack within the magazine. 55

Upon the return-movement of the actuating-ring, the opposite effects occur, the feed-clamps being first swung out of engagement 60 with the stack, and the feed-ring being thereafter turned back to its original position. The pressure with which the feed-clamps engage the stack is regulated by the degree of friction produced against the feed-ring by 65 the friction-plug 106.

The extent of the advancing movement of the stack, at each operation of the feed-clamps, is limited by the stop-arms 24 to that amount necessary to take up such space as has been left vacant by the removal of 70 an article by the feed-plate 26, and since the thickness of the articles may be variable, provision is necessary for producing only the requisite and more or less variable amount of advance in the stack. Such provision is afforded by the construction including the spring-housing 84 and the spring 90, for these parts are adapted to yield whenever the oscillating movement of the feed-ring and of the actuating-ring is arrested 75 by engagement of the end of the stack with the stop-arms 24, and, by designing the cam 104 to give an amplitude of movement sufficiently great for all contingencies, an operation is insured in which the stack will be 80 fed with certainty to the required extent, and will then be yieldingly pressed against the stop-arms with a force regulated by the spring 90. 85

Since the feeding movements of the feed-clamps are, for convenience in construction, horizontal, while the articles fed move in a path which is downwardly inclined, the advance of the stack involves a slight relative sliding movement, in a vertical direction, between the individual articles and the clamps. This movement is not sufficient, however, to substantially affect the operation of the machine, especially as the teeth extend vertically across the feed-clamps, and the 90 movement of the clamps is therefore, for practical purposes, sufficiently approximate in direction, to the advancing movement of the stack. 95

While the invention has been described as 105 embodied in mechanism designed particularly for feeding articles of sheet-material, and more especially articles of a tapering or wedge-like form such as are employed in the manufacture of shoe-heels, it will be 110 apparent that the invention is not limited to such embodiment, and that, in general, it is susceptible of embodiment in various forms within the scope of the following claims. 115

What is claimed as new is:

1. Feed-mechanism for a shoe machine having, in combination, means for holding tapering articles of sheet heel material in a curved stack with their tapering faces in engagement and normal to the curvature of 120 the stack and for advancing them in the direction of the length of the stack; and means for discharging successive articles from the end of the stack. 125

2. Feed-mechanism having, in combination, means for holding tapering articles in a spiral stack with their thin ends disposed at the inner periphery of the stack and for advancing them in the direction of the length of the stack; and means for discharg- 130

- ing successive articles from the end of the stack.
3. Feed-mechanism comprising means for holding articles in a curved stack with the plane of the articles normal to the curvature of the stack and for advancing the articles, in the direction of the length of the stack, by concurrent engagement with the inner and outer surfaces of the stack.
- 10 4. Feed-mechanism for a shoe machine comprising means for holding tapering articles of sheet heel material stacked in close engagement with each other and with their thicker and thinner extremities respectively together; and means for advancing the stack in the curved line of its longitudinal extension.
- 15 5. Feed-mechanism having, in combination, a stack-holder in the form of a descending spiral for receiving articles to be fed; means for regulating the descent of said articles by concurrent engagement with the inner and outer peripheries of the stack; and means for discharging articles successively from the lower end of the stack.
- 20 6. Feed-mechanism having, in combination, two oppositely-disposed members, respectively concave and convex in form, between which articles are held in the form of a curved stack, said members being movable substantially in the direction of the length of the stack; and means for so moving at least one of said members to advance the stack longitudinally.
- 25 7. Feed-mechanism comprising a cylindrical member, guide-members arranged helically about the cylindrical member and spaced therefrom so as to produce in conjunction therewith a spiral path for a stack of articles to be fed and means coöperating with said cylindrical member for feeding said articles along the spiral path.
- 30 8. Feed-mechanism comprising a cylindrical member, and guide-members arranged helically about the cylindrical member and spaced therefrom so as to produce a spiral path for a stack of articles to be fed, the cylindrical member being rotatable to promote the advance of the stack through said path.
- 35 9. Feed-mechanism comprising means for holding articles in a curved stack, including a convex guide member engaging the concave surface of the stack, and a series of concave feed-members engaging the convex surface of the stack and intermittently movable to advance the stack longitudinally.
- 40 10. Feed-mechanism comprising means for holding articles in a curved stack, and a feed-member arranged to engage a surface of the stack intermittently and movable, when in such engagement, in a path curved approximately in the direction of the longitudinal extension of the stack, to advance the stack longitudinally.
- 45 11. Feed-mechanism comprising means for holding articles of sheet-material in a curved stack and for advancing the stack longitudinally, said means including curved devices for clamping the articles by edge-wise pressure, and mechanism for moving said devices approximately in the direction of the length of the stack. 70
- 50 12. Feed mechanism comprising means for holding articles of sheet-material in a curved stack and for advancing the stack longitudinally, said means including a series of devices for clamping the articles by intermittent edgewise pressure, and mechanism for moving each of said devices, while engaged with the articles, approximately in the direction of the length of the stack. 75
- 55 13. Feed-mechanism for a shoe machine comprising means for holding tapering articles of sheet heel material in a curved stack, with the thicker and thinner extremities of the articles respectively together, and means for discharging articles from the end of the stack. 80
- 60 14. A magazine, for wedge heel-lifts, comprising members between which the lifts may be stacked in close engagement with each other and with their thicker and thinner extremities respectively together, said members having curved surfaces conforming to the longitudinal curvature of the stack so produced. 85
- 65 15. Feed-mechanism having, in combination, a stack-holder in the form of a descending spiral for receiving a plurality of uniformly tapering articles in stacked relation with their tapering faces in engagement and normal to the curvature of the stack; and means for positively advancing the stack as a whole down the spiral. 90
- 70 16. Feed-mechanism having, in combination, correspondingly curved coöperating members for gripping a plurality of articles in face-to-face relation in a curved stack by engagement with the respective ends of said articles; and means for actuating said coöperating members to cause the stack of articles to be fed. 100
- 75 17. Feed-mechanism having, in combination, means for holding to be fed a curved stack of articles disposed on edge in face-to-face relation, said means comprising a cylindrical inner member for engaging the corresponding sides of said articles, and a helically arranged outer member spaced therefrom and coöperating therewith to support and guide the curved stack; and means for feeding said articles in the direction of the stack. 110
- 80 18. Feed-mechanism comprising means for holding articles in face-to-face relation in a spiral stack; a plurality of movable members adapted to surround and engage the outer edges of all the articles in said stack; and means for intermittently effecting 120
- 85 19. Feed mechanism comprising means for holding articles in face-to-face relation in a spiral stack; a plurality of movable members adapted to surround and engage the outer edges of all the articles in said stack; and means for intermittently effecting 130

said engagement and causing said members to actuate the stack step-by-step in the direction of said holding means.

19. A magazine for tapering articles, comprising a plurality of substantially cylindrical members between which said articles are stacked with their tapering faces in close engagement and normal to the curvature of said members and the thick and thin ends thereof in engagement respectively with the outer and the inner curved members.

20. A curved magazine for holding a plurality of articles having uniformly tapering faces that are stacked together in face-to-face engagement with the corresponding

ends of said articles disposed together, comprising members having curved surfaces conforming to the longitudinal curvature of the stack so produced between which the articles are stacked, and means for advancing said articles through said magazine.

21. A magazine for tapering articles, comprising a plurality of cylindrical members between which said articles are stacked with their tapering faces in close engagement and disposed normal to the curvature of said members, and means for feeding said articles through said magazine.

ERASTUS E. WINKLEY.
